DESIGN FOR AN ASH TRAY

Phillip Steve Kushiner, Detroit, Mich.

Application October 25, 1939, Serial No. 87,863

Term of patent 3½ years

To all whom it may concern:

Be it known that I, Phillip Steve Kushiner, a citizen of the United States, residing at the city of Detroit, in the county of Wayne and State of Michigan, have invented a new, original, and ornamental Design for Ash Trays, of which the following is a specification, reference being had to the accompanying drawing, forming part hereof.

Fig. 1 is a perspective view of an ash tray showing my new design.

Fig. 2 is a side elevational view thereof, the tray portion being shown in section; and

Fig. 3 is an end elevational view.

I claim:

The ornamental design for an ash tray, as shown.

PHILLIP S. KUSHINER.
